UNITED STATES PATENT OFFICE

165,895

PAD HOLDER

Amerigo Angeli, Milwaukee, Wis.

Application February 26, 1951, Serial No. 14,323

Term of patent 14 years

(Cl. D44—29)

To all whom it may concern:

Be it known that I, Amerigo Angeli, a citizen of the United States, residing at Milwaukee, in the county of Milwaukee, and State of Wisconsin, have invented a new, original, and ornamental Design for a Pad Holder, of which the following is a specification, reference being had to the accompanying drawing, forming a part thereof.

I claim:

The ornamental design for a pad holder, as shown.

AMERIGO ANGELI.
